T. S. WILES.

Machine for Moistening the Fold Lines of Collars.
No. 234,156. Patented Nov. 9, 1880.

UNITED STATES PATENT OFFICE.

THOMAS S. WILES, OF ALBANY, NEW YORK.

MACHINE FOR MOISTENING THE FOLD-LINES OF COLLARS.

SPECIFICATION forming part of Letters Patent No. 234,156, dated November 9, 1880.

Application filed September 8, 1879.

To all whom it may concern:

Be it known that I, THOMAS S. WILES, of the city of Albany, in the county of Albany and State of New York, have invented certain Improvements in Devices for Moistening the Line of Fold in Turn-Down Collars, of which invention the following is a specification, reference being had to the accompanying drawings.

Turn-down collars of linen and similar woven fabrics are starched and ironed flat and stiff, and afterward folded or turned down in a curved line along the upper edge of the neck-band portion. The proper folding or turning down of such starched and ironed flat stiff collars is usually difficult and liable to strain and break the threads in the outer layers thereof, so that many such collars are commonly spoiled in being folded.

The general object of my present invention is to produce devices by the use of which a person can rapidly, evenly, and nicely moisten the curved line of fold in flat stiff-starched and ironed collars, and thereby facilitate the even folding over of the outer face portion upon the band part and greatly lessen the liability of breaking or injuriously straining the fabric of the collar along the line of fold.

In the aforesaid drawings, in which like parts are marked by like letters in the different figures, Figure 1 is a central longitudinal section and elevation of a machine which embodies one form of this invention. Fig. 2 is an elevation of one end part, Fig. 3 a cross-section at the line *z z*, Fig. 4 a section at the line *y y*, and Fig. 5 a horizontal section at the line *x x* and plan of some parts below that line, all of the same machine. Fig. 6 is a sectional elevation of some parts of the same machine on a larger scale. Fig. 7 is a sectional side elevation, and Fig. 8 an end elevation, of a part of a machine which embodies another form of a portion of this invention.

A is the stationary part of the machine. B and C are two feed-rollers, both dry and one or both made narrow, and shaped so that a person can freely pass and guide through between them, when turning together, variously-shaped collars, each in the particular curved course of its line of fold, without dampening any part of the collar by its contact with the rollers.

D is a line-moistening device, constructed and arranged so that its liquid-delivering point or part *e* shall be in contact with and discharge a limited quantity of liquid against one surface 55 of the curved line of fold *w*, Fig. 5, in a collar, V, while the latter is being properly passed through between the rollers, so as to thereby progressively moisten the line of fold. The line-moistener D is arranged with its discharge-point *e* in, or nearly in, the plane *u u* of the axes of the two rollers B C, in order to thereby apply the liquid to the line of fold in a flat stiff-starched and ironed collar being passed between the rollers without requiring 60 the collar to be bent along and against a part 65 of the curved surface of one of the rollers, and so that the line-moistener can begin to wet the line of fold at the forward end of the collar as soon as that end shall be entered between the 70 rollers, and shall complete the moistening of the line of fold as soon as the rear end of the collar shall leave the rollers.

I also arrange the liquid-delivering point *e* of the line-moistener beyond and adjacent to 75 one end of that one of the feed-rollers which is adapted to act against that side of the collar to which the line-moistener is adapted to apply the liquid, substantially as represented 80 in the drawings, in order to thereby moisten the line of fold in the collar while passing only the band portion *s* between the two rollers, and thus prevent the rollers from marring or 85 injuring the finished outer face portion, *r*, of the collar in the line-moistening operation.

In and around that one of the two rollers B C which is adapted to bear against that side of the collar to which the line-moistener is adapted to apply the liquid I form an annular recess, *f*, to receive the usual thick raised 90 seam *t* on the back side of the ironed collar along the junction of the band part *s* and turn-down portion *r*, and so that the recess *f* shall thereby serve as a guide to assist in directing the collar in the proper curved course past the 95 delivery part *e* of the line-moistener, and thereby cause the moistening of the collar on its back side in a line parallel to the said raised seam.

In order to facilitate the accurate presentation of the collars to the rollers B C and line-moistener D, and to guard against accidental 100

marring and wetting of the finished surface of the ironed collar outside of the line of fold by the said rollers and line-moistener, I combine and arrange therewith a guard-plate, G, substantially as shown in the drawings.

In the above-described combinations and arrangements of the feed-rollers and line-moistener the latter can be in the form of a split, grooved, or tubular reservoir, ruling-pen, 10 or striping device of any suitable kind.

In Figs. 7 and 8 the line-moistener is in the form of a liquid-holding reservoir, h, having spongy material therein, and a tubular ruling or striping outlet, i, and secured upon and 15 moving with the support J of the upper feed-roller, which latter, in that case, has the annular recess f for receiving the raised seam t on the back of the collar.

As a commonly-preferred device, I combine 20 with the feed-rollers B C a line-moistener in the form of a narrow liquid-holding circular rim, k, Figs. 1, 2, and 6, secured to or upon one end of the lower roller, C, so as to be revolved with or by that roller and with about the same 25 surface speed as the latter, the liquid being supplied or applied to the rim k by any suitable means—as, for instance, from a reservoir by a tube bearing at its open end against the rim k.

30 As an improvement, I combine and arrange with the feed-rollers B C and rotary line-moistener k a liquid-holding reservoir, L, and a circular liquid-carrying disk, M, arranged to revolve with its upper edge against the rim k 35 and its lower edge in the liquid in the reservoir, so as to thereby transfer a limited quantity of the liquid to the rotary line-moistener, and thence to the line of fold in a collar passing between the rollers.

40 The feed-roller C and rotary line-moistener k are secured to, so as to be revolved with and by, a shaft, N, journaled in the stationary part A, and having a pulley, N', or hand-crank N², by which that shaft can be rotated. The roller 45 B is secured upon, so as to be turned with and by, a shaft, O, which is journaled in a frame, J, that is pivoted at p p to the stock A, so that the roller B is movable a little away from and toward the other feed-roller. The liquid-supplying disk M is secured to, so as to be revolved by and with, a shaft, Q, which is journaled in a frame, R, that is pivoted at q q to the stock A, so that the disk M is thus movable a little away from the line-moistener k.

55 A spring, P, between the stock A and pivoted frame R causes the rim of the disk M to bear gently against the line-moistening rim k, and a spring, S, between the pivoted frame J and stock A serves to lift the roller B away

60 from the roller C to permit the insertion of a collar whenever the force of the spring S is not overcome, as by foot or other pressure upon a treadle or stirrup, n, connected by a strap, rod, or link, m, to the frame J, and by which latter

65 device, or other suitable means, the roller B is to be pressed on the collar V against the roller C with suitable yielding force to cause the pas-

sage of the collar through between the rollers and along the delivery part e of the line-moistener as the rollers B C revolve.

The shaft N of the roller C and rim k has fast thereon a gear, T, engaging with a gear, U, fast on the shaft O of the roller B, and with a gear, W, fast on the shaft Q of the disk M, and these parts are preferably all proportioned 75 and arranged so that the rollers B C, line-moistening rim k, and disk M shall all positively revolve together with about equal surface speed.

The liquid-carrying parts k and M can consist of circular pieces of felt d, Fig. 6, or other suitable liquid-holding material, secured between solid circular plates b, or the parts M and k can be very fine-toothed wheels.

The moistening-liquid can be of any suitable kind, as water or a mixture of water and glycerine.

What I claim as my invention is—

1. The combination, with the two dry feed-rollers adapted to pass a collar through between them without dampening it, of a line-moistener, substantially such as described, having its liquid-delivering point in, or nearly in, the plane of the axes of the two feed-rollers and beyond and near to one end of the 95 bearing-surface of that feed-roller which is adapted to act against that side of the collar to which the line-moistener is adapted to apply the liquid, as set forth.

2. The combination, with the two dry feed-rollers B C, having the annular recess f in one 100 of them, of a line-moistener, substantially such as described, having its liquid-delivering point in, or nearly in, the plane of the axes of the two feed-rollers and beyond and near one end 105 of the bearing-surface of that feed-roller in which is the recess f, and which is adapted to bear against that side of the collar to which the line-moistener is adapted to apply the liquid, as set forth.

3. The combination of the two feed-rollers, the line-moistener, and the collar-guiding guard-plate G, substantially as described.

4. The combination, with the two dry feed-rollers B C, of the circular line-moistener k, 115 concentric with and fast to the end of the feed-roller C, and means, substantially as specified, for supplying liquid to said circular line-moistener, as set forth.

5. The combination of the feed-rollers B C, 120 rotary line-moistener k, liquid-feeding disk M, and devices, substantially as described, for gently pressing the liquid-feeding disk against the line-moistener, and for pressing one feed-roller against and moving it away from the 125 other feed-roller, as set forth.

In testimony whereof I hereunto set my hand, in the presence of two subscribing witnesses, this 5th day of September, 1879.

THOMAS S. WILES.
